UNITED STATES PATENT OFFICE.

CHARLES P. ALLEN, OF DENVER, COLORADO.

WOODEN PIPE.

SPECIFICATION forming part of Letters Patent No. 359,590, dated March 22, 1887.

Application filed April 22, 1886. Renewed February 10, 1887. Serial No. 227,180. (No model.)

To all whom it may concern:

Be it known that I, CHARLES P. ALLEN, a citizen of the United States, residing at Denver, in the county of Arapahoe and State of Colorado, have invented certain new and useful Improvements in Wooden Pipes; and I do hereby declare the following to be a full, clear, and exact description of the invention, such as will enable others skilled in the art to which it appertains to make and use the same.

This invention relates to hooped pipes made of wooden staves.

My improvement consists, first, in interlocking the staves at the cross-joints by a metallic tongue, and, secondly, of a metallic hoop composed of an approximately circular strap-bolt and a coupling-shoe so combined that the hoops can be tightened around the pipe after it has been placed around the same.

20 In the annexed drawings, Figure 1 represents a side elevation of a portion of my improved wooden pipe. Fig. 2 represents a cross section thereof. Fig. 3 represents a side elevation of a wooden pipe in which the staves are arranged to break joints. Fig. 4 illustrates the coupling-shoe in section and the ends of the strap-bolt in elevation. Fig. 5 represents a plan of the coupling-shoe. Fig. 6 illustrates a stave end, showing the metallic tongue seated 25 in the groove of the same. Figs. 4 to 6 are drawn to a larger scale than Figs. 1 to 3.

The same letters of reference indicate identical parts in all the figures.

A groove, *a*, is cut in each end of each stave 35 A deep enough to permit the entrance of a metallic tongue, *B*, about half way, as shown in Fig. 6. The length of the metallic tongue is a little in excess of the width of the stave, so that the ends of the tongue may project a little from each side of the stave to enter the edges of the adjoining staves, as shown in Fig. 40 2, when two abutting stave ends are driven up.

The concealed metallic tongue will then interlock the abutting stave ends with the adjoining staves, and thus form an excellent cross-joint. The hoops are composed of an approximately circular strap-bolt, *C*, and a coupling-shoe, *D*. The coupling-shoe is engaged from opposite ends by the respective ends of the strap-bolt. To this end the coupling-shoe is 45 constructed with a socket for the T-headed end of the strap-bolt, and with a reverse socket for the nutted end of the strap-bolt, the construction of these sockets and the length of the strap-bolt being such, as shown in Fig. 4, that the end of the strap-bolt carrying the nut will 50 overlap and hold in place the T-headed end thereof. The nut affords the means for tightening the strap-bolt around the pipe to the necessary degree. 55

I claim as my invention—

1. A hooped pipe made of wooden staves which are interlocked at each cross-joint by a concealed metallic tongue seated in grooves in the abutting stave ends and projecting a little 60 at each side thereof into the edges of the adjoining staves, substantially as before set forth.

2. A pipe made of wooden staves hooped by hoops composed each of an approximately circular strap-bolt and a coupling-shoe which 65 engages the head at one end of the strap-bolt and the nut at the other end thereof.

3. A hoop composed of an approximately circular strap-bolt and a coupling-shoe, the strap-bolt having a head at one end and a nut 70 at the other end for engaging the coupling-shoe from opposite ends, substantially as before set forth.

In testimony whereof I affix my signature in presence of two witnesses.

CHARLES P. ALLEN.
